VAPOR GENERATOR

Stanfield N. Arnold, Lexington, Ky., and George E. Tate, Summit, N.J., assignors to Foster Wheeler Corporation, New York, N.Y., a corporation of New York

Application January 24, 1955, Serial No. 483,588

4 Claims. (Cl. 122—235)

This invention relates to vapor generators and more particularly to pressure fired vapor generators.

Pressure-fired vapor generators, that is, those fired with combustion air under high pressure, generally comprise a cylindrical casing in which vapor generating tubes are arranged to substantially surround a combustion chamber and to extend substantially parallel and/or inclined, to the longitudinal axis of the casing. In a number of pressure-fired vapor generators, some of the vapor generating tubes line the combustion chamber in heat exchange relationship with the combustion gases, both by radiation and convection, while the remaining tubes are arranged outside the combustion chamber and are disposed in the path of flow of combustion gases discharged from the chamber as to be heated by convection alone. The vapor generating tubes, outside the combustion chamber, generally are arranged so that the combustion gases pass over successive tubes or in a direction normal to the axes of the tubes so that some tubes are subjected to higher temperature gases than others whereby non-uniform heat absorption results.

The present invention contemplates a novel vapor generator wherein maximum efficiency of operation is obtained.

In accordance with the present invention a novel vapor generator is provided which effects, among other things, substantially the same or equal heat absorption by each of the vapor generating tubes. The vapor generator comprises a cylindrically shaped boiler casing which is provided with a combustion chamber lined with vapor generating tubes extending substantially parallel to the longitudinal axis of the chamber. An annular gas passage is arranged concentric with the combustion chamber and has disposed therein circumferentially arranged vapor generating tubes in heat exchange relationship with combustion gases which flow out one end of the combustion chamber and in a direction parallel to the axes of the tubes. Second and third annular gas passages are arranged in the casing in communication with the first-mentioned gas passage and have disposed therein superheater and vapor generating tubes, respectively. The third annular gas passage communicates with an economizer which receives combustion gases from the third passage and conducts the gases in heat exchange relationship with feed liquid flowing to the vapor generator.

The foregoing advantages of the present invention will appear more fully hereinafter, from a consideration of the detailed description which follows taken together with the accompanying drawings wherein an embodiment of the invention is illustrated by way of example.

In the drawings:

Fig. 1 is a front elevational view of a vapor generator embodying the present invention;

Fig. 2 is an elevational view, in section, of the boiler of Fig. 1;

Fig. 3 is a transverse section of the boiler taken along the line 3—3 of Fig. 2;

Fig. 4 is an elevational view of the superheater as-

2

sembly of Fig. 2 and is illustrated apart from the boiler to more clearly show the arrangement of tubular elements thereof; and

Fig. 5 is an elevational view, in section, of the economizer of Fig. 1.

Referring now to the drawings and more particularly to Fig. 1 thereof wherein an embodiment of the invention is clearly illustrated, the reference numeral 11 generally designates a vapor generator which comprises a cylindrical and horizontally arranged liquid and vapor vessel 12, a boiler 13 and an economizer 14. A pair of parallel downcomer conduits 15 and 16 each have one end connected to the lower portion of drum 12 and extend toward boiler 13. Conduits 15 and 16 are connected at intermediate portions by a transverse conduit 17 to which is connected one end of a downcomer conduit 18. One upper end of a downcomer conduit 19 is connected to conduit 15 and a similar end of a conduit 20 is connected to downcomer 16 adjacent to and below conduit 17. Downcomers 15 and 16 extend vertically along and below boiler 13 and then run upwardly through a casing 21 of boiler 13 for connection to a ring-shaped supply header 22 at diametrically opposite points thereof (Fig. 2). Supply header 22 is rectangular in transverse cross-section and is disposed at the lower portion of casing 21. Downcomer conduit 18 extends similarly as conduits 15 and 16 but projects centrally through casing 21 for connection to a ring-shaped header 23 arranged within the space encompassed by header 22. Header 23 is provided with a circular wall 24 which separates the header into an inner chamber 25 and an outer chamber 26. Openings 27 are provided in wall 24 to communicate chamber 25 with chamber 26. Headers 22 and 23 are joined together by an annular strip 28 which is fastened to both headers, as for example, by welding.

A circular wall or partition 29 is disposed in casing 21 coaxial with the longitudinal axis of the latter and extends from the upper portion of the casing downwardly to a point above headers 22 and 23 to define a furnace or combustion chamber 30. A substantially cone-shaped refractory member 31 is disposed below the lower edge of wall 29 to define a floor for the furnace. A plurality of upright boiler or vapor generating tubes 32 line the side of wall 29, facing the furnace, and are connected at their lower ends to header 23. Tubes 32 extend from the combustion chamber to below the lower edge of wall 29 and then run substantially parallel to the sides of floor 31 to separate into three separate, circumferential and concentric rows 33, 34, and 35. Tubes 32 of innermost row 33 are connected to chamber 25 of header 23 while tubes 32 of rows 34 and 35 are connected to chamber 26. The portions of tubes 32 in combustion chamber 30 are substantially in contact with each other except between the lower edge of wall 29 and furnace floor 31 where the tubes of rows 33 and 34 are bent away from the tubes of row 35 toward the axis of the furnace to provide spaces for passage of combustion gases from the combustion chamber; the space between the lower edge of wall 29 and furnace floor 31 defining a gas outlet 36 for discharging combustion gases from the furnace. The upper ends of furnace tubes 32 are connected to a circular header 37, formed in casing 21, and the header is connected to liquid and vapor vessel 12 by a plurality of riser conduits 38.

An inlet conduit 39 is connected to a source of combustion supporting fluid (not shown) under pressure and to the upper portion of casing 21 and centrally thereof, and communicates with a chamber 40 within casing 21. Chamber 40 has a plurality of vanes 41 disposed therein, adjacent outlets 42 formed in the lower portion of the chamber whereby the combustion supporting fluid under pressure, entering chamber 40 is discharged through out-

lets 42 and given a swirling motion about the axis of the furnace. A fuel conduit 43 connected to a source of fuel (not shown) extends through conduit 39 and chamber 40 to terminate in a firing nozzle 44 at the bottom of chamber 40. The fuel for firing combustion chamber 30 is a fluid, as for example, oil and the combustion supporting fluid may be air or oxygen.

A second circular wall or partition 45 is disposed in casing 21 and is spaced from and concentric with wall 29. Wall 45 extends upwardly from adjacent header 22 and together with wall 29 defines a circular or annular gas passage 46 for receiving gases discharged through gas outlet 36. A plurality of primary convection tubes 47 are arranged in gas passage 46 in directions parallel to tubes 32, and are divided into two circumferential rows, one row being arranged adjacent wall 29 and the second row being arranged adjacent wall 45; the rows of tubes 47 being spaced apart to provide passage of gases therebetween. Some of the tubes 47 in the row adjacent wall 45 and above the upper edge of the latter are bent to provide for passage of gases from gas passage 46 while some of the tubes 47 of the row of tubes adjacent wall 29 are bent to provide for passage of gases from combustion chamber 30 into gas passage 46. The lower ends of tubes 47 are connected to header 22 and the upper ends of the tubes are connected to a circular header 48 formed in the upper portion of the casing 21, which header is arranged concentric with header 37. Header 48 is connected to liquid and vapor drum 12 by a plurality of riser tubes 49. An inclined baffle 50 is provided across tubes 32 and 47, adjacent furnace floor 31, to prevent the passage of gases from chamber 30 toward headers 22 and 23.

A third circular wall or partition 51 is disposed in casing 21 and is arranged concentric with walls 29 and 45 to define with the latter a second circular or annular gas passage 52. A superheater assembly 53 is disposed in gas passage 52 and comprises helically wound superheater tubes 54, arranged in five concentric rows or layers 55, 56, 57, 58 and 59 (Figs. 2-4). Each layer consists of a plurality of tubes 54 and the pitch of the helices of each tube are the same. The pitch is determined so that between each pair of convolutions of one tube, a single complete 360 degrees turn of each of eleven tubes is provided, whereby each of the layers includes twelve tubes. The invention is not to be construed as limiting each of the layers to the above number of helical tubes but rather the number is dependent upon design considerations. Furthermore, the length of the tubes in the different layers is not the same because the length of the tubes of a particular layer is a function of the diameter and height of said layer. A superheater tube 54A of outermost layer 59 is shaded in Fig. 4 to more clearly illustrate the pitch of the tubes and the number of tubes in between each pair of convolutions.

Layer 55 surrounds substantially the entire outside surface of wall 45 to cool the latter during operation of the vapor generator whereas layer 59 lines substantially the entire inside surface of wall 51 for cooling purposes also. As is more clearly shown in Fig. 4, the end portions of each of the superheater tubes are bent substantially at right angles to the intermediate portion of its respective tubes and extend in vertical directions. The lower end portions of tubes 54 are connected to a ring-shaped inlet superheater header 60, rectangular in cross-section, which is disposed concentric with supply headers 22 and 23, and the upper end portions of the superheater tubes are connected to a similar shape outlet superheater header 61 disposed in the upper portion of casing 21. A plurality of connecting conduits 62 communicate inlet header 60 with an inlet manifold 63 which is connected to vapor and liquid vessel 12. A conventional baffle-type dryer 64 is arranged in vessel 12 for removing moisture from the vapor in the latter and communicates with inlet manifold 63 to provide the latter with substan-

tially dry vapor. A plurality of connecting conduits 65 are connected to outlet header 61 and project outside casing 21 to communicate header 61 with a superheated vapor outlet conduit 66.

5 A plurality of upright vapor generating or secondary convection tubes 68 are arranged circumferentially in a third circular or annular gas passage 69, substantially defined by wall 51 and a wall 69A next to casing 21. Gas passage 69 communicates at its lower end with passage 52 to receive combustion gases therefrom and with a casing gas outlet 70 (Figs. 1 and 2) for discharging combustion gases from the casing. The lower ends of vapor generating tubes 68 are connected to a circular inlet header 71, formed in casing 21, and the header is connected to the lower ends of tubes 19 and 20. The upper ends of vapor generating tubes 68 are connected to a circular outlet header 72, formed in the upper portion of casing 21, and the header is connected to vapor and liquid drum 12 by a plurality of vertically disposed riser conduits 73.

Economizer 14 (Figs. 1 and 5) comprises a vertical casing or shell 75 and has disposed therein three vertically arranged and concentric cylindrical walls or partitions 76, 77 and 78, respectively. Partition 76 provides a gas passage 79 while partition 77 cooperates with partition 76 to define a gas passage 80. Partition 77 cooperates with partition 78 to define a gas passage 81 and partition 78 cooperates with the inner surface of casing 75 to define a gas passage 82. A group of helically arranged tubes 83 are disposed in gas passage 80 and are arranged in the same manner as the superheater tubes 54 in casing 21. In the case of tubes 83, the tubes are arranged in seven concentric rows or layers and the pitch of the helices of the tubes are such that seven tubes are provided between each pair of convolutions of a particular tube. The lower portions of tubes 83 are bent substantially at right angles to the intermediate portions of the tubes and are connected to a ring-shaped feed liquid inlet header 84 which in turn is connected to a feed liquid inlet conduit 85. Conduit 85 projects through the bottom of casing 75 and is connected to a source of feed liquid (not shown). The upper end portions of tubes 83 are bent in the same manner as the lower ends and are connected to an upper ring-shaped outlet header 86 disposed in gas passage 80 and in alignment with lower header 84. A second group of helically wound tubes 87 are disposed in gas passage 81 and comprise eight concentric layers with six tubes between each pair of convolutions of a particular tube. The lower ends of tubes 87 are connected to a ring-shaped inlet header 88, arranged concentric with header 84 and header 88 is connected to upper outlet header 86 by a connecting conduit 89 which passes centrally of passage 79. The upper end portions of tubes 87 are connected to an outlet header 90 arranged concentric with header 86 and in alignment with lower header 88. A connecting conduit 91 is connected to outlet header 90 and communicates the latter with a perforated pipe 92 arranged within vapor and liquid vessel 12. A cover 93 is arranged at the top of gas passages 80 and 81 and openings 94 are provided in the cover. Cover 93 serves to seal passage 81 from the space at the top of casing 75 while openings 94 serve to communicate passage 80 with the upper portion of the casing. A cover 95 is provided at the lower edges of partitions 76 and 77 and the cover is formed with openings to accommodate feed liquid inlet conduit 85 and a gas outlet 97 which communicates with the lower portion of gas passage 80. Cover 95 serves to seal gas passage 80 from the space in the lower portion of casing 75. Covers 93 and 95 are each provided with an aligned central opening to freely communicate both ends of passage 79 with the upper and lower portions of the casing 75, respectively. A gas outlet conduit 98 is connected to the upper portion of casing 75 for discharging combustion gases from the casing. A damper or valve 99 is pro-

vided in conduit 98 and is operable for controlling the flow of combustion gases from the casing. A second valve 100 (shown only in Fig. 1) is connected in outlet conduit 97 for controlling the flow of gas through the conduit. Conduits 97 and 98 may be connected to further heat recovery apparatus, or connected for discharging to the atmosphere as desired.

In operation, combustion supporting fluid, as for example air or oxygen, under pressure is delivered through conduit 39 and chamber 40 whence it passes into combustion chamber 30 in a swirling stream. At the same time a fluid fuel, as for example, oil is delivered through feed conduit 43 and through firing nozzle 44 where the fuel is atomized and thence projected into the swirling combustion air for intimate mixture with the latter. The fuel air mixture is then ignited whereby gases of combustion are formed in the combustion chamber and the gases pass out of the latter through the lower end of the chamber at gas discharge outlet 36. The combustion gases flow upwardly in gas passage 46 in heat exchange relationship with vapor generating tubes 47. The combustion gases are discharged from the upper portion, or end, of passage 46 and then the gases flow downwardly in gas passage 52 and over superheater tubes 54 in heat exchange relationship with the latter. From gas passage 52 the combustion gases flow upwardly in passage 69 in heat exchange relationship with vapor generating tubes 68. The gases in passage 69 then flow out of the latter at the upper portion thereof and are discharged from the casing through gas discharge outlet 70.

Heated feed liquid, as for example, water is delivered to vapor and liquid vessel 12 through conduit 92. The water in vessel 12 flows through downcomer conduits 15 and 16, thence into transverse conduit 17 and conduit 18, and in connecting conduits 19 and 20. The water in conduit 18 is conducted into chambers 25 and 26 of header 23 thence through tubes 32 where part of the water is changed to steam. The steam in boiler tubes 32 passes into header 37 whence it is conducted through riser tubes 38 into vessel 12 where the steam is collected in the vapor space of the vessel. The water in conduits 15 and 16 passes into header 22, thence through tubes 47, whence the steam generated therein passes into header 48 and into vessel 12 by way of riser tubes 49. The water in conduits 19 and 20 passes into circular header 71 and thence into tubes 68 where steam is generated. The steam from tubes 68 passes into outlet header 72 whence it is conducted through riser tubes 73 to the vapor space of the vapor and liquid vessel 12. The steam in vessel 12 passes through dryer 64 where most of the moisture is removed, thence into superheater inlet manifold 63 whence it is conducted to connecting conduits 62. The steam from conduits 62 passes into superheater inlet header 60, thence through tubes 54 of superheater assembly 53 where the steam is superheated by the combustion gases passing over the tubes. The superheated steam then passes out of the superheater assembly and into outlet header 61 whence the superheated steam is conducted by tubes 65 into superheated steam outlet conduit 66.

It will now be apparent that the vapor generator of the present invention provides for uniform heat absorption by the vapor generating tubes by reason of the flow of combustion gases in a direction parallel to the longitudinal axes of the vapor generating tubes. Since the heat input to or heat absorbed by the vapor generating tubes of a circumferential row is substantially equal and the length of said tubes are also substantially equal, uniform flow of fluids in the tubes is provided whereby distributing plugs, generally employed in vapor generators where the flow is unequal, are not required in the present invention. Furthermore, the arrangement of helical superheater tubes in the present invention provides for more simple structure in that less superheated tubes are

necessary than in conventional arrangements so that fewer superheater tube end connections to headers are required and circular and concentric headers may be employed.

The combustion gases passing through gas discharge conduit 76 enter gas passage 81 of economizer 14 and flow downwardly in heat exchange relationship with the tubes 87 of the passage. The gases in passage 81 are then discharged through the lower end thereof and flow upwardly through gas passages 79 and 82 and into the space at the upper portion of casing 75. When furnace 30 is fired with an air-fuel mixture, valve 100 in conduit 97 is closed and valve 99 in conduit 98 is opened. Consequently, the combustion gases from passages 79 and 82 pass into the upper space of casing 75 and then flow through conduit 98 and past valve 99. On the other hand, when furnace 30 is fired with an oxygen-oil mixture, valve 99 in conduit 98 is closed and valve 100 is opened. In such event, the combustion gases from gas discharge conduit 70 flow into gas passage 81 then downwardly and out of the bottom of the latter to flow upwardly in passages 79 and 82. The gases in passages 79 and 82 then flow into the upper space of casing 75 thence through openings 94 in cover 93 and downwardly in gas passage 80 in heat exchange relationship with the tubes 83 therein. The gases in passage 80 pass out of the bottom through the opening in plate 95 thence through conduit 97 past valve 100. In the case of the oxygen-oil firing of combustion chamber 30, the resulting combustion gases are passed through both gas passages 80 and 81 in order to utilize the heat obtained by condensing the steam in the combustion gas; it being understood that the oxygen in the combustion gases combines with the hydrogen to yield steam. The combustion gases resulting from the firing of the air-oil mixture in chamber 30 are conducted through passage 81 only, because most of the heat of the combustion gases is given up in passing through passage 81 alone.

Water from the source of feed water (not shown) is conducted through feed liquid conduit 85 into lower header 84. From header 84 the water passes upwardly through tubes 83 in passage 80 and in heat exchange relationship with the gases flowing therethrough. The heated feed water from tubes 83 in passage 80 is then collected in upper header 86 whence the water passes through conduit 89, in passage 79, and into lower circular header 88. Feed water in header 88 is then conducted through tubes 87 of passage 81 whence it is collected in header 90. Conduit 91 conducts the water from header 90 and delivers it into perforated pipe 92 in drum 12 and thereafter the water flows into the downcomer conduits.

It will now be apparent that the vapor generator of the present invention provides a novel economizer which is adapted for maximum efficiency both in the case of the firing of air-oil mixture in chamber 30 and oxygen-oil firing in the chamber. In either case optimum utilization of the heat contained in the combustion gases from chamber 30 is effected.

Although one embodiment of the invention has been illustrated and described in detail, it is to be expressly understood that the invention is not limited thereto. Various changes can be made in the design and arrangement of the parts without departing from the spirit and scope of the invention as the same will now be understood by those skilled in the art.

65 What is claimed is:

1. In a vapor generator of the class described adapted for burning an air-oil mixture and an oxygen-oil mixture, a vapor and liquid vessel, a substantially cylindrical casing, means defining a cylindrical combustion chamber in said casing having a combustion gas outlet, means for firing said combustion chamber whereby combustion gases are formed therein, means forming a first annular gas passage surrounding said combustion chamber and communicating with said gas outlet to receive combustion gases therefrom for travel in a direction parallel to the

longitudinal axis of said combustion chamber, a plurality of vapor generating tubes disposed in said first gas passage and in communication with said vapor and liquid drum, said vapor generating tubes being arranged in a direction parallel to said axis of said combustion chamber and in heat exchange relationship with the combustion gases flowing in said first gas passage, means forming a second annular gas passage surrounding said first gas passage and communicating with the latter to receive combustion gases for travel therein, a plurality of vapor conducting tubes disposed in said second gas passage and in heat exchange relationship with the combustion gases therein, said vapor conducting tubes being in communication with said vapor and liquid vessel to receive vapor therefrom, a casing gas discharge outlet in the cylindrical casing and in communication with said second gas passage to receive combustion gases therefrom, a second cylindrical casing having an inlet in communication with said gas discharge outlet, means forming a third annular gas passage in said second cylindrical casing and in communication with said inlet, means forming a fourth annular gas passage in said second cylindrical casing arranged concentric with said third gas passage and in communication therewith, a plurality of liquid conducting tubes disposed in said third and said fourth gas passages in communication with each other and with a source of feed liquid, means communicating said liquid conducting tubes with the vapor and liquid drum to conduct feed liquid thereto, and means for causing combustion gases from said casing gas outlet to flow through said third gas passage only and preventing flow of combustion gases through said fourth gas passage when an air-oil mixture is burned in the vapor generator.

2. The vapor generator set forth in claim 1 wherein means are provided for forming a fifth annular gas passage concentric with said third and said fourth gas passages and in communication therewith, and wherein valve means are provided which are operable in first predetermined positions to cause the combustion gases to flow through only said third gas passage when an air-oil mixture is burned, and which are operable in second predetermined positions to cause the combustion gases from said third gas passage to pass successively through said fourth and said fifth gas passage when an oxygen-oil mixture is burned.

3. In a fluid heat exchange apparatus of the class described, an elongated gas casing having an inlet for receiving heating fluid and a pair of outlets for discharging heating fluid from said casing, means forming a first annular gas passage in communication with said inlet for receiving heating fluid and with one of said pair of outlets, means forming a second annular passage arranged concentric with said first annular passage and in communication with the latter and with the other of said pair of outlets, a plurality of tubes arranged in both said

10 15 20 25 30 35 40 45 50 55

passages and in communication with a source of fluid to be heated, said tubes being disposed in heat exchange relationship with heating fluid passing through said passages, and control means operable in first positions for causing heating fluid to pass through said first passage and said one outlet without passing through said second passage and said other outlet, and operable in second positions for causing the heating fluid to pass through said first and second passages and through said other outlet only.

4. In fluid heat exchange apparatus of the class described, an elongated cylindrical casing having an inlet for receiving heating fluid and a pair of outlets for discharging the heating fluid from said casing, means forming a first annular passage in communication with said inlet for receiving the heating fluid and with one of said pair of outlets, means forming a second annular passage concentric with said first passage and in communication with the other of said outlets, means forming a third annular passage concentric with said first and said second passages and communicating the latter with each other to provide the second passage with heating fluid from said first passage, a plurality of tubes arranged in both said first and said second passages and in communication with a source of fluid to be heated, said tubes being disposed in said first and said second passages in heat exchange relationship with the heating fluid flowing through the associated passage, a first valve means for said one outlet and movable to a first position to cover said one outlet and movable to a second position to uncover said one outlet, second valve means for said other outlet and movable to a first position to uncover said other outlet and movable to a second position to cover said other outlet, said valve means, when moved to their respective first positions, causing the heating fluid from said first passage to pass through said third and said second passages successively and out of the casing through said other outlet, and when moved to their respective second positions, causing the heating fluid from said first passage to flow through said one outlet without passing through said second passage.
